United States Patent

Des. 236,243
Patented Aug. 12, 1975

236,243

HALTER

Harry W. Froehlich, 1344 Marineie Road,
Pacific Palisades, Calif. 90272

Filed Apr. 12, 1974, Ser. No. 460,504

Term of patent 3½ years

Int. Cl. D2—02

U.S. Cl. D2—353

FIG. 1.

FIG. 2.

FIG. 3.

FIG. 1 is a front perspective view showing my new design for a halter;

FIG. 2 is a rear perspective of the same; and

FIG. 3 is a side view as seen from the left in FIG. 1.

I claim:

The ornamental design for a halter, as shown.
